UNITED STATES PATENT OFFICE.

EDWIN RINGOLD, OF CINCINNATI, OHIO, ASSIGNOR TO THE BRUNSWICK-BALKE-COLLENDER COMPANY, OF OHIO.

DESIGN FOR A MAIN ENTRANCE FOR BAR-ROOMS.

SPECIFICATION forming part of Design No. 24,685, dated September 17, 1895.

Application filed April 6, 1895. Serial No. 544,680. Term of patent 7 years.

To all whom it may concern:

Be it known that I, EDWIN RINGOLD, of Cincinnati, in the county of Hamilton and State of Ohio, have invented a certain new and useful Design for a Main Entrance for Bar-Rooms; and I do hereby declare that the following is a full, clear, and exact description of the same, reference being had to the accompanying drawing, forming part of this specification.

My invention relates to a design for the main entrance to the bar in a café or drinking establishment.

The accompanying drawing, which forms part of this specification, presents an elevation or face view of the design.

In the drawing D D are two cabinet-like cupboards that are arranged on either side of the doorway leading to the bar, and which in one sense form a part of the cabinet-work partition of the café, which separates the bar from that portion of the café located in front of said partition.

C C are parts of the partition that extend, respectively, from the inner or more adjacent sides of the cabinets D D to the side posts or pilasters a a of the doorway, the tops of the members C C being formed with cornices to match the cornice portions of the cabinets, as clearly shown. The lowermost portions of the partition members C C and the door-posts a a and the cabinets D D are all formed with slightly-projecting bases, as seen, and each post a has that portion which is on a level with the cornice of the adjacent member C formed with moldings to match those of said cornice, while above this part of each member A is an ornamental capping or top piece b. In each of the partition members C is set an oval glass e, which may be either translucent or mirror-like, and between the posts a a are arranged fancy short doors f f, hinged, respectively, to said posts, each door comprising a frame the interior of which is rectangular and filled with a fancy glass panel, while the bottom of each is curved inwardly and upwardly from each side to a point about centrally beneath the glass panel, and the top of each is curved upwardly and inwardly in

ogee form, and thence downwardly and toward the inner top corner, all as shown in the drawing. As will be seen, the small double doors f f are of such length and are so disposed (in a vertical direction) relatively to the posts a a as to leave (when closed) open spaces to the doorway above and below, that are approximately equal, and which, in the aggregate, about equal the space occupied by the doors lengthwise. Over these doors f f and between the upper ornamented portions of the posts a a is a sort of network g, the lower edge of which spans the space between the posts in the form of an arch, while the upper edge is scroll-like in pattern and curved inwardly and upwardly from each post in ogee lines, that meet at the central top part, where an ornamental solid piece surmounts the open-work g. As shown, in the middle of this open-work g is a solid shield-like device or member i, which may carry on its face a monogram; but these details of my design I do not consider very essential, the striking feature of the design, so far as the portal of the partition is concerned, being the posts a a, surmounted with the fancy tops b b, the fancy open-work device g, spanning the space (arch-like at the lower edge) between the upper portions of said posts and extending centrally upward in curved lines at its top, and the fancy short doors, and the characteristic features of the design, so far as the partition proper is concerned, being the members C C, having oval glasses at e e, and the cabinets D D, as shown. These cabinets, it will be seen, have each a fancy top member m, centrally surmounted by an ornamental member that corresponds with the one at the top of the portal member g, and also have each two top corner ornaments smaller than but shaped like the top-most portions of the door-posts a a.

Having so fully shown and described my invention that others can produce my new design, what I claim as new, and desire to secure by Letters Patent, is—

1. The herein described and shown design for the portal of a bar-room main entrance, the characteristic features of which are the

24,685

posts a, a, having the fancy top portions b, b; the open-work member g, spanning the space between the upper portions of the post members; and the short door members f, f; substantially as set forth.

2. The herein shown and described design of the partition-like portion of the bar-room main entrance, the characteristic features of which are the members C, C, having oval

glasses at e, e; and the cabinets D, D; all arranged as set forth.

In witness whereof I have hereunto set my hand this 20th day of December, 1894.

EDWIN RINGOLD.

In presence of—

ADOLF VOLLMER,
JULIUS BALKE.
